ATTORNEYS.

UNITED STATES PATENT OFFICE.

GEORGE GREEN, OF CORPUS CHRISTI, TEXAS.

FEED-WATER HEATER.

SPECIFICATION forming part of Letters Patent No. 352,464, dated November 9, 1886.

Application filed June 17, 1886. Serial No. 205,414. (No model.)

To all whom it may concern:

Be it known that I, GEORGE GREEN, of Corpus Christi, in the county of Nueces and State of Texas, have invented a new and Improved 5 Feed-Water Heater for Steam-Boilers, of which the following is a full, clear, and exact description.

The object of my invention is to provide a boiler with a feed-water heater which will 10 serve as a spark-arrester, and which will also purify the water and prevent the formation of scale in the boiler, and whereby, also, the heating-surface will be increased and fuel economized.

15 The invention consists of a feed-water heater composed of a series of pipes attached to half-cylindrical heads, placed diagonally in the fire-box of the boiler, and connected with the water-space of the boiler.

20 The invention also consists of various parts and details and combinations of the same, as will be fully described hereinafter, and then pointed out in the claims.

Reference is to be had to the accompanying 25 drawings, forming a part of this specification, in which similar letters of reference indicate corresponding parts in both figures.

Figure 1 is a longitudinal sectional elevation 30 of my improvement, and Fig. 2 is a sectional plan view of the same on the line $x-x$ of Fig. 1.

The boiler A is provided with the fire-box B, the flues C, and the grate-bars D, of the usual construction. In the fire-box B is placed diagonally the feed-water heater E, which consists of a series of pipes, F, opening at their 35 ends into the half-cylindrical heads G and G', of which the former is placed in the rear of the fire-box B, near the upper edges of the grate-bars D, and is provided with an inlet- 40 pipe, H. The other head, G', is placed near the crown-sheet I in the front of the fire-box, and is provided on each side with the pipes J, which connect the head G' with the water-compartment K of the boiler.

The feed-water passes from the inlet-pipe H 45 into the feed-water heater E, and through the same and out into the water-compartment K of the boiler by means of the pipe J.

It will be seen that the water passing through the feed-water heater E is quickly heated, as 50 the latter is in direct contact with the fire on the grate-bars D. The water in the heater E is purified by being heated, the impurities settling in the head G, so that the water which passes into the water-compartment K is prevented from forming scales in the boiler. It 55 will also be seen that the cinders, sparks, &c., are arrested by coming in contact with the pipes F and the heads G and G' of the heater E, which deflect the sparks back into the fire 60 on the grate-bars D, which consumes the sparks. Sufficient space is left between the pipes F for the passage of the heat and smoke from the grate-bars to the flues of the boiler.

Having thus fully described my invention, 65 I claim as new and desire to secure by Letters Patent—

1. In a boiler, the combination of a fire-box with a feed-water heater consisting of pipes opening into half-cylindrical heads, an inlet-pipe connected with one head, and an outlet-pipe connecting the other head with the water-compartment of the boiler, substantially as 70 shown and described.

2. In a boiler, the fire-box B, the boiler-flues 75 C, the grate-bars D, and the water-compartment K, in combination with the feed-water heater E, consisting of the pipes F and the heads G and G', the inlet-pipe H, and the outlet-pipes J, connecting the head G' with the 80 compartment K of the boiler, substantially as shown and described.

GEORGE GREEN.
